UNITED STATES PATENT OFFICE.

NELS J. LUNDEEN, OF TACOMA, WASHINGTON.

BRACKET FOR TABLE LEAVES.

Application filed December 29, 1921. Serial No. 525,563.

To all whom it may concern:

Be it known that I, NELS J. LUNDEEN, a citizen of the United States, and residing at Tacoma, in the county of Pierce and State 5 of Washington, have invented certain new and useful Improvements in Brackets for Table Leaves, of which the following is a specification.

This invention relates to brackets, and 10 has particular reference to a means for supporting foldable filler leaves for extension tables.

The invention herein disclosed is a continuation in part of an application filed 15 November 29, 1921, Serial No. 518,497.

The main object of my invention is to provide a simple and inexpensive bracket or support for filler leaves of extension tables, which leaves may be stored beneath 20 the permanent table top sections, whereby they are in a convenient position for use when the table is extended.

With this and other objects in view, my invention consists of the parts and combination 25 of parts as will hereafter appear.

In the drawings:

Figure 1 is a side elevation of the device in folded position, having a table leaf associated therewith,

Fig. 2 is a side elevation, partly in section, of the device in extended position, and

Fig. 3 is a perspective view of the device.

Referring more particularly to the drawings, the numeral 1 indicates the bridge or 35 pedestal cap of an ordinary commercially used extension table, which in effect constitutes the base upon which the leaves, hereinafter mentioned, are mounted.

As is known in the art, filler leaves are 40 usually in two sections, same being indicated at 2 and 3, the sections being hingedly secured together by means of hinge members 4, section 2 of the foldable filler leaf being pivotally secured to the bracket, as 45 will be hereinafter more fully described.

The bracket forming the present invention comprises two substantially rectangular frames 5 and 6, frame 5 being of smaller area than frame 6. Frame 6 is pivotally secured to pedestal cap 1, by means of elements 7. The frame 5 is free from attachment to the pedestal cap 1, but is connected at its upper end to the upper end of frame

6 by means of a loosely pivoted spacing link 8, and is connected at its lower end to 55 the lower end of frame 6 by means of a loosely pivoted link 9, the link 9, it is obvious, forming pivots 10 and 11 at frames 5 and 6, respectively. A reinforcing strap 12 is provided which extends between the sides 60 of frame 6.

Section 2 of the leaf is suitably secured to the frame 5 by means of staples 13 so so that the leaf can be maintained in a horizontal position when being raised into 65 operative position or lowered into storage, the link 8 serving as an abutment to support said leaf.

In use, the main leaves of the table, with which this bracket is employed, are extended 70 to expose the folded sectional leaves which, when stored, assume the position illustrated in Figure 1. The leaf which it is desired to raise is then bodily lifted which will swing the frame 6 on pivots 7 to the position 75 illustrated in Fig. 3, and during this movement the frame 5, due to its pivotal mounting, will assume the position shown in Figs. 2 and 3, when section 3 of the leaf may be extended.

What I claim is:

1. The combination with a supporting leaf adapted to be moved to stored position, of a bracket comprising an arm pivotally secured at its lower end to a base, a second 85 arm pivotally secured at its upper end to said leaf, a strap pivotally connecting the upper ends of said arms and spacing said ends from each other and a strap pivotally connecting the lower ends of said arms. 90

2. The combination with an extension table leaf adapted to be moved to stored position, of a bracket comprising a frame pivotally secured at its lower end to a base, a second frame pivotally secured to said 95 first mentioned frame at the upper and lower portions of each, and to said table leaf, and a reinforcing element for said first mentioned frame.

3. The combination with an extension 100 table leaf adapted to be moved to stored position, of a bracket comprising a main frame pivotally secured to a base, a secondary frame, a link connecting the main and secondary frames at the upper portion of 105 each, a link connecting the main and second-

ary frames at the lower portion of each, and a reinforcing element for said main frame.

4. The combination with an extension table leaf adapted to be moved to stored position, of a bracket comprising a main frame pivotally secured to a base, a secondary frame secured to said table leaf, pivoted

means connecting the lower ends of said main and secondary frames, and a pivotally mounted abutment link connecting the upper ends of said main and secondary frames and spacing said frames from each other. 10

In testimony whereof I affix my signature.
NELS J. LUNDEEN.
